UNITED STATES PATENT OFFICE.

FRANK B. COOK, OF CHICAGO, ILLINOIS.

POLARIZED ELECTROMAGNETIC APPARATUS.

SPECIFICATION forming part of Letters Patent No. 699,660, dated May 13, 1902.

Application filed August 29, 1899. Serial No. 728,819. (No model.)

To all whom it may concern:

Be it known that I, FRANK B. COOK, a citizen of the United States of America, and a resident of Chicago, Cook county, Illinois, have 5 invented certain new and useful Improvements in Polarized Electromagnetic Apparatus, of which the following is a specification.

By reason of the peculiar application of my invention for the purpose I shall describe 10 and illustrate it in connection with that class of apparatus known as "polarized electric bells," which are generally used at the subscribers' stations of a telephone system for signaling the subscriber to come to the telephone. My invention, as will appear, is not, 15 however, confined to such an application.

In what are termed "party-line" circuits, to be hereinafter more particularly described, it has hitherto been necessary to wind the 20 electromagnet-coils of the subscribers' bells in such manner as to provide for high impedance, in order to prevent a short circuit of the talking-currents, and to accomplish this result it has been customary to wind the 25 coils of the electromagnet with wire of a smaller cross-section and also increase the length of the core of the said magnet.

My invention consists in the provision of a magnetic conducting - casing which surrounds 30 the electromagnet, thereby affording a means of protection against fire should the coil of the electromagnet burn out and also providing by the addition of the casing increased impedance or self-induction sufficient 35 to adapt the apparatus for use in a party-line circuit, or, in fact, for any circuit arrangement in which the electric bell is bridged across between the leads of the circuit while conversation is being carried on.

40 My invention has certain other objects in view; and it consists in certain other features about to be described, reference being now had to the accompanying drawings, in which—

Figure 1 is a side elevation of my improved 45 electromagnet arrangement, showing the permanent magnet and base in section. Fig. 2 is an edge or top view with the bells removed. Fig. 3 is a detail view showing the spring attachment for an apparatus operated by a 50 straight current. Fig. 4 is an end view with the permanent magnet partly broken away. Fig. 5 is a cross-section on the line xx of

Fig. 2. Fig. 6 is a detail sectional view through the electromagnet-casing. Fig. 7 is a detail view showing an adjustable armature. Fig. 8 is a like view showing the end of the shell tapered. Fig. 9 is a diagrammatic view of a party-line bridging system, showing my improved bell apparatus included in such a system. 55

My invention as an electric bell for telephone uses is what is known as a "polarized" bell, which consists of a permanent magnet and an electromagnet, the combined influence of which elements is brought to bear upon the bell-armature. The permanent magnets A and A² are magnetically connected, respectively, to the two parts B and B² of the inclosing shell or casing for the electromagnet D by the non-magnetic screws 60 aa , which pass through the supporting-frame D² and secure the permanent magnets and two parts of the casing to the said frame. This frame D² is secured to the base D³ and supports the parts. The inclosing shell (designated generally at E) is of magnetic conducting material and completely incloses the electromagnet, and as the core D⁴ of the electromagnet D is magnetically connected to the two parts B and B² of this casing, Fig. 1, the 65 core, the shell, and the armature form a nearly-complete magnetic circuit. The ring-armature H, Fig. 5, is pivoted or hinged at one side of or at a point beyond the side of the casing, as designated at bb , and encircles 70 the electromagnet D. This armature is therefore disposed between the ends of the two parts B and B² of the magnetic casing or shell, so that the polarized ends thereof act directly upon the armature. The bell-striker arm J, 75 between the two bells J² J², is attached to and carried by the armature H. With an alternating current the ends of the two parts of the shell or casing are of different polarities, and a combined push and pull is brought 80 to bear upon the armature. The ends of the permanent magnet, also brought to bear upon the armature H, are of the same relative polarity, thus permanently polarizing the armature with one magnetic polarity. 85

In Fig. 3 I have shown an attachment to be used when a straight current is employed which is capable of ready attachment to or detachment from the bell, consisting of a 90

prolongation or extension-piece K of the armature, a bracket K², removably held on the permanent magnets by the screws a a, having a holding-arm K³, a spring K⁴, secured to the extension of the armature, and an adjusting-screw K⁵ for the spring. This device is capable of ready removal and can be reversed in position as desired to exert an opposite pull on the armature when a current of opposite polarity is used.

It will be observed that the lines of force of the magnet-poles of the shell or casing act directly upon the armature, and the whole arrangement is such as to produce a more sensitive action of the armature. This sensitiveness of action is obtainable particularly because of the close and intimate proximity of one part of the armature to the poles of the shell, which proximity is always maintained during the vibrations of the bell-striker. To bring the armature in still closer proximity, the ends of the magnetic shell or casing may be tapered, as shown in Fig. 7, to afford space for the necessary vibration of the armature, and yet position a part of the armature near its pivot in still closer proximity to the poles of the shell. As shown in Fig. 7, the armature may be formed in two parts which are adjustable toward and away from each other by the adjusting-screw d in order to regulate the stroke of the armature. As the electromagnet is completely inclosed, should it burn out under an excessive current the communication of fire to other apparatus or to the building is avoided. The construction as a whole is compact.

In party-line systems such as illustrated in Fig. 9 the subscriber's apparatus is bridged across between the leads 25 and 26 of the line-circuit from the central-office jack 27. The electric bell 28 at each station is inclosed in a bridge 29 of its own, and the generator 30 and receiver 31 and transmitter 32, constituting the telephone set, are connected in series with each other in another bridge, as shown, and in parallel with the electric bell. In such an arrangement as stated it is necessary that the electric bell should be of high impedance or self-induction in order to prevent the voice-currents from short-circuiting across the bridge 29. This high impedance or self-induction is obtained in my invention by the magnetic conducting shell or casing about the electromagnet, and it is therefore

unnecessary to increase the size of the electromagnet to accomplish this desired end. So, also, in any instance where the bell is bridged between the leads of the circuit the construction and apparatus of my invention in and of itself affords the necessary impedance or self-induction.

It is evident that the armature itself may be a permanent magnet, and thus be polarized.

Having thus described my invention, what I claim as new therein, and desire to secure by Letters Patent, is—

1. In a polarized electromagnetic apparatus the combination of a polarized and pivoted armature, a two-part magnetic casing or shell, said armature being positioned between the ends of the two-part shell and said casing or shell surrounding the electromagnet.

2. In a polarized electromagnetic apparatus, the combination of a polarized and pivoted armature, a two-part magnetic casing or shell, said armature encircling the electromagnet and positioned between the ends of the shell and said shell surrounding the electromagnet.

3. An electromagnetic apparatus, consisting of an armature, a two-part magnetic shell or casing, an extension of said armature, a bracket and a spring connected with the armature and bracket, together with means for regulating the tension of the spring.

4. In a polarized electromagnetic apparatus the combination of a polarized and pivoted armature, a two-part magnetic casing or shell having a tapered end or index, said armature being positioned between the ends of the two-part shell and said casing or shell surrounding the electromagnet.

5. In a polarized electromagnetic apparatus, the combination of a polarized and pivoted armature, a two-part magnetic shell, and a divided armature positioned between the ends of the casing or shell and means for adjusting the parts of the armature in relation to said ends, the said casing or shell surrounding the electromagnet.

Signed by me at Chicago, Cook county, Illinois, this 26th day of August, 1899.

FRANK B. COOK.
